LOOM HARNESS

Frank H. Kaufmann, Huntingdon Valley, Pa., assignor to Steel Heddle Manufacturing Company, Philadelphia, Pa., a corporation of Pennsylvania

Application October 17, 1957, Serial No. 690,653

4 Claims. (Cl. 139—92)

This invention relates to loom harness, and it relates more particularly to the provision of means for reducing the wear of the contacting parts where the end portions of the heddle supporting rods are mounted in the end struts of the frame.

Heretofore, in the construction of loom harness frames, the common practice has been to pass the end portions of the heddle supporting rods through slots in the end struts of the frame. In some instances securing devices, in the nature of spring hooks, were secured to the end struts of the frame with the otherwise free ends thereof engaging apertures in the end portions of the heddle supporting rods.

One of the principal objections to such construction was that where the end portions of the heddle supporting rods passed through the end struts of the frame, by reason of each being made of metal, considerable wear took place, both at the end portions of the heddle supporting rods and at the upper and lower ends of the slots in the end struts through which the rods passed. The wear was caused because of the constant shifting of the stresses when the heddle frame was raised and lowered, during the operation of the loom, to form the successive sheds of the warp.

When such wear takes place it is frequently necessary to replace the heddle supporting rods even though they are otherwise in serviceable condition, and in the modern forms of loom harness frames, in which the heddle supporting rods are permanently secured to the means for holding the same intermediate their ends, this is even more difficult and expensive.

In other instances, it is sometimes necessary to entirely discard the harness frame, when the wear takes place at the ends of the slots in the end struts of the frame, through which slots the end portions of the heddle rods extend.

The principal object of the present invention is to provide simple and efficient means for reducing the wear on the end portions of the heddle supporting rods, and at the ends of the slots in the end struts of the heddle frame through which the ends of the heddle rods pass.

The nature and characteristic features of the present invention will be more readily understood from the following description, taken in connection with the accompanying drawing forming part hereof, in which:

Figure 1 is a front elevation of a loom harness frame embodying the main features of the present invention;

Fig. 2 is an enlarged view, partly in elevation, and partly in section, of a portion of the corner structure of the frame shown in Fig. 1; and

Fig. 3 is a vertical section taken on the line 3—3 of Fig. 2.

It should, of course, be understood that the description and drawing herein are illustrative merely, and that various modifications and changes may be made in the structure disclosed without departing from the spirit of the invention.

Referring to the drawing, the loom harness frame shown

2

therein may be of any preferred type employing top and bottom rails 10 and end struts 11. The heddle supporting rods 12 are positioned in the frame in the usual locations adjacent the top and bottom rails 10, and have the heddles 13 slidably mounted thereon in the usual and customary manner.

The heddle rods 12 are supported intermediate their ends in any desired manner preferably so that longitudinal movement of said heddle rods in the frame will be limited or prevented. Likewise, the ends of the heddle rods 12 may be secured in any of the well known ways.

If the supporting devices nearest the ends of the frame are such that longitudinal movement of said heddle rods in the frame will be limited or prevented, and are substantially close to the end struts 11, it is not ordinarily necessary to use securing devices at the ends of the heddle supporting rods, as the same may be permitted to pass freely through suitable apertures 14 in the end struts 11, and be seated therein.

20 Each of the metallic strips used for forming the end struts 11 is provided, at each of the places where the ends of the heddle supporting rods 12 pass therethrough, with a suitable slot 14 the width of which is equal to the thickness of the heddle supporting rod.

25 At the end of each slot 14 through which the heddle supporting rod 12 passes, said slot 14 is enlarged as at 15 for the mounting therein of a block 16, preferably made of shock resisting material, such as nylon or the like, which is made tightly fitting in the enlargement 15 of the slot 30 14 in which it is mounted so as to be retained in place therein. Of course, other means of retaining the blocks 16 in place may be used if desired.

By the provision of the blocks 16 of wear resisting material, the top and bottom edges of the heddle supporting rod 12 will be effectively protected against the wear which usually occurs between the abutting surfaces of the edges of the heddle supporting rods and the ends of the slots through which said heddle supporting rods pass.

40 By the foregoing arrangement, the wear which usually occurs at the ends of the heddle supporting rods and which results in a relative short life of the same is eliminated to a considerable extent, and replacement of the heddle supporting rods while the greater portions thereof are still in relatively good condition will not be required.

45 Such wear as does occur will be in the bearing blocks 16 which, of course, may be inexpensively replaced when required.

While the bearing blocks 16 are shown as being of rectangular cross-section, it should, however, be noted that blocks of any other preferred shape in cross-section may be used.

50 It should also be noted that the invention may be employed in loom harness frames in which there are used spring hooks or tongues having their free ends engaging apertures in the ends of the heddle rods, which spring hooks or tongues are mounted either on the inner or outer side of the end struts.

I claim:

60 1. In a loom harness frame comprising top and bottom rails connected by end struts, said end struts having slots therein, and heddle supporting rods the end portions of which extend through said slots, the combination therewith of bearing blocks for the end portions of the heddle supporting rods mounted at the ends of the slots in the end struts.

65 2. In a loom harness frame comprising top and bottom rails connected by end struts, said end struts having slots therein, and heddle supporting rods the end portions of which extend through said slots, the combination therewith of blocks of wear resistant material mounted at the

ends of the slots providing bearings for the end portions of the heddle supporting rods.

3. In a loom harness frame comprising top and bottom rails connected by metallic end struts, said end struts having slots therein, and heddle supporting rods the end portions of which extend through said slots, said slots each extending above the top and below the bottom edges of the heddle rod the end of which extends therethrough, and blocks of wear resistant material mounted in the ends of said slots providing bearings for the end portions of the heddle supporting rods.

10

4. In a loom harness frame comprising top and bottom rails connected by metallic end struts, said end struts having slots therein, and heddle supporting rods the end portions of which extend through said slots, said slots having enlargements at the ends thereof, and blocks of wear resistant material mounted in said enlargements at the ends of the slots providing bearings for the end portions of the heddle supporting rods.
